UNITED STATES PATENT OFFICE.

WILLIAM N. BEST, OF NEW YORK, N. Y.

LIQUID-FUEL BURNER.

1,232,756.

Specification of Letters Patent. Patented July 10, 1917.

Application filed January 22, 1917. Serial No. 143,603.

To all whom it may concern:

Be it known that I, WILLIAM N. BEST, a citizen of the United States, and resident of New York city, in the county of Kings and 5 State of New York, have invented certain new and useful Improvements in Liquid-Fuel Burners, of which the following is a specification.

This invention relates to certain improvements in liquid fuel burners and more particularly to a type adapted for use in open hearth furnaces for melting steel or other alloys or retaining the desired high temperature in other types of furnaces such as soaking 10 pit furnaces, etc.

In an open hearth furnace, if the oil is delivered by placing the burner in the rear wall of the regenerator end of the furnace, difficulty is experienced due to the fact that 15 the burner itself becomes excessively hot, due to localized heat and the brick lining of the regenerator end burns out.

One object of my invention is to so design, support and place the burner that the 20 atomized product may be delivered at a point between the air inlet ports and the metal bath, excessive localized heating avoided, and the heat more efficiently and effectively utilized.

Further objects of my invention are to 25 maintain the temperature of the burner itself comparatively low to avoid excessive heating of the burner and to provide means by which the burner may be easily raised or 30 lowered to different positions at the will of the operator or quickly removed from the furnace.

In the accompanying drawings, to which 35 reference is to be had, I have illustrated one form which my invention may assume and have illustrated one type of furnace in connection with which that form may be employed. It will of course be obvious that 40 various changes in the details of construction of the burner itself may be made within the scope of my invention as defined in the appended claims and that the burner may be used with other types of furnaces than that illustrated. In these drawings, 45

Figure 1 is a horizontal section through the regenerator end of an open hearth furnace and showing my burner in position;

Fig. 2 is a central vertical section through the construction shown in Fig. 1;

Fig. 3 is a central longitudinal section 55 through the burner itself upon a larger scale than that of Figs. 1 and 2;

Fig. 4 is an end view of the delivery end of the burner;

Fig. 5 is a transverse section on the line 60 5—5 of Fig. 3;

Fig. 6 is an end view of the burner piping, and

Figs. 7 and 8 are front and side elevations 65 of the burner support.

I have illustrated my improved burner as mounted in the end wall of the reverberatory portion of an open hearth furnace. The furnace is illustrated as having a lining of fire brick or other refractory material externally supported and bound together by suitable tie-rods and I-beams. At one end of the body portion 10 which contains the metal to be melted or otherwise heat-treated is the mixing chamber and reverberatory 70 portion 11. In the common construction in which the gas is used as the fuel, the gas enters said chamber through a centrally disposed passage 12 leading upwardly through the floor of said chamber and between two 80 air inlet passages. The air and gas become mixed in the chamber 11 and pass downwardly toward the body portion 10. In applying my improved burner to this type of furnace, I support the burner adjacent to the 85 outer surface of the end wall 14 and as an important feature I make it of such a length that the atomized fuel is liberated at a point approximately midway between the air inlet passages 13 and the metal containing 90 body 10.

In the specific form of burner illustrated, I employ two concentric tubes 15 and 16, the inner one of which serves as a conduit for the atomized fuel while the annular space between the two serves as a circulating passage 95 for cooling water. The two tubes 15 and 16 are held rigid in respect to each other and in spaced relationship at their inner ends by a nozzle member 17. This is shown as of 100 annular form with two internally threaded, concentric, cylindrical flanges receiving the ends of the two tubes and having an annular chamber 18 communicating with and acting as an end for the annular space between the 105 two tubes.

The central opening through the member 17 and which communicates with the pas-

sage through the inner tube 15 is preferably contracted vertically and elongated horizontally so as to form an outlet or delivery slot 19 as is shown particularly in Fig. 4. The 5 atomized fuel delivered through the conduit 15 as hereinafter described, by means of the formation of this slot, is projected in a flattened fan-shaped sheet directly toward or over the mass to be heated. The nozzle is 10 back a sufficient distance from the mass of material to be treated so that the fan-shaped sheet at its point of engagement with or passage over the material is of a width approximately equal to the width of the chamber 10 15 so that the material is uniformly treated across its entire width.

The burner, as previously stated, projects through the end wall of the reverberatory portion of the furnace. Outside of the furnace, the two tubes are spaced and held rigid in respect to each other by an annular fitting 20. The inner tube 15 extends through a stuffing box 21 in the rear wall of the fitting, and supply and delivery conduits 22 25 and 23 for cooling water are connected to opposite sides of said fitting. Preferably, the supply conduit 22 is connected to a pipe 24 which extends lengthwise of the annular water chamber to a point adjacent the nozzle 17 so that the cooling water is delivered to said annular space near the nozzle 17 and can flow back through the annular passageway to the outlet 23. In order to hold the conduits properly spaced intermediate of 30 their ends, any suitable number of supporting set screws or other spacing means 35 may be employed. I have shown one such construction in Fig. 5.

For supporting the burner and facilitating its adjustment, I provide a standard or bracket 26, one form of which is shown particularly in Figs. 7 and 8. This includes two vertically extending plates or flanges 27 spaced apart at their upper ends a sufficient 40 distance to receive the tube 16 therebetween. The tube is provided with a collar 28 which may be adjusted lengthwise of the burner and has oppositely extending trunnions 29 seated in notches, sockets, or bearings, in the 45 upper ends of the plates or flanges 27. At a short distance back from the collar 28, I provide a second collar 30 which may also be adjustable lengthwise of the tube 16 and which has a depending flange or pair of 50 spaced flanges 31. A turn buckle 32 or other equivalent means adapted to be readily adjusted as to length connects the collar 30 and the base or lower end of the bracket 26 so that by means of the said turn buckle the 55 burner may be swung in a vertical plane, about the trunnions 29 as an axis.

For atomizing the liquid fuel and delivering it through the conduit 15 to the nozzle 17, I provide an atomizing device which is 60 65 preferably of the general character shown in

the patent to W. N. Best, Jr., No. 963,985, issued July 12, 1910, or in my prior Patent No. 752,195, issued February 16, 1904.

Oil, tar, or other liquid fuel is delivered through a conduit 33 and steam, compressed 70 air or other atomizing fuel is delivered through a conduit 34 and across the fuel outlet. The mixture of atomized fuel and the atomized gaseous medium travels through the conduit 15 at high speed and 75 becomes mixed even more fully than at the atomizer itself. The mixture is projected from the nozzle 17 in a fan-shaped sheet as hereinbefore stated while the air constituting the main supporter of the combustion 80 enters the chamber 11 through the conduits 13 and flows in the direction of the burner toward and past the nozzle 17 where the combustion takes place. This air, together with the jacket water, keeps the temperature 85 of the burner from getting too high while the positioning of the nozzle substantially at the point indicated causes the main portion of the combustion to take place where it will operate to the best advantage on the 90 mass to be treated.

By means of the turn buckle, the burner may be elevated or lowered in accordance with the character or mass of the material to be treated, while by adjusting the positions of the collars 28 and 30, the portion of the burner within the body of the furnace may be readily adjusted. It is of course evident that the conduits 15 and 16 may be made of various different lengths, depending upon the character of the furnace in connection with which the burner is to be employed. By means of the turn buckle, the burner may be quickly lowered until it is in such position that the trunnions may be lifted 95 from their supports, the pin connecting the turn buckle to the collar 30 may be removed, and the burner may be quickly and easily removed from the furnace.

Having thus described my invention, what 100 I claim as new and desire to secure by Letters Patent is:

1. A liquid fuel burner comprising a tube having a delivery nozzle at one end, an atomizer detachably secured to the opposite 115 end for delivering a liquid fuel and a fuel atomizing gaseous medium to said tube, a water jacket encircling said tube, and extending from said nozzle to a point adjacent to but spaced from said atomizer, and 120 means engaging with said water jacket for pivotally supporting said burner and permitting it to swing in a vertical plane.

2. In combination, a furnace having air inlet openings at one end, a burner projecting through the end wall to a point beyond said openings, a bracket outside of said furnace and pivotally supporting said burner, means connected to said burner in the rear of said bracket for swinging said burner in 130

- a vertical plane, means for delivering a liquid fuel and a fuel atomizing gaseous medium to the rear end of said burner, and a water jacket encircling said burner and 5 extending to the inner end of the latter.
3. A liquid fuel burner including two concentric tubes, spaced apart to form a water jacket therebetween, the inner tube being longer than the outer tube, an annular 10 member connecting said tubes at one end, and constituting a nozzle, a coupling including a packing connecting said members at the opposite end of the outer tube and encircling the inner tube and having an inlet 15 and an outlet for cooling water to the jacket, and an atomizer detachably secured to one end of the inner tube and serving to deliver an atomized liquid fuel and a fluid-atomizing gaseous medium through the inner tube 20 to said nozzle.
4. A liquid fuel burner including two concentric tubes spaced apart to form a water jacket therebetween, the inner tube being longer than the outer tube, an annular member 25 connecting said tubes at one end and constituting a nozzle, a coupling including a packing connecting said members at the opposite end of the outer tube and encircling the inner tube and having an inlet and an 30 outlet for cooling water to the jacket, an atomizer detachably secured to one end of the inner tube and serving to deliver an atomized liquid fuel and a fluid-atomizing gaseous medium through the inner tube to 35 said nozzle, a collar encircling said outer tube intermediate of its ends and presenting oppositely disposed trunnions, a second collar encircling said outer tube intermediate said first mentioned collar and said coupling, and means secured to said last mentioned 40 collar for tilting said burner upon its trunnions.
5. A liquid fuel burner including a tube having a nozzle at one end, means for delivering liquid fuel and a fuel-atomizing 45 gaseous medium to the opposite end, a pair of trunnions intermediate of the ends of said tube, a bracket having a pair of vertically disposed flanges receiving said tube therebetween and supporting said trunnions, and 50 a link of adjustable length also secured between said flanges and secured to said tube in the rear of said trunnions.
6. A liquid fuel burner including a pair 55 of concentric tubes spaced apart to form a water jacket therebetween, an annular member connecting said tubes at one end, said member having two concentric annular flanges interiorly threaded to receive the ends of said tubes, and an elongated flattened central passage communicating with the inner flange and inner tube, means for delivering cooling water to the annular space between said tubes, and means for delivering an atomized liquid fuel through 60 the inner tube.

Signed at New York, in the county of New York, and State of New York this 19th day of January, A. D. 1917.

WILLIAM N. BEST.
